US00D936415S

(12) **United States Design Patent** (10) **Patent No.:** **US D936,415 S**
Seum et al. (45) **Date of Patent:** **** Nov. 23, 2021**

(54) **DISPENSER**

- (71) Applicant: **PepsiCo, Inc.**, Purchase, NY (US)
(72) Inventors: **Michael T. Seum**, Chicago, IL (US);
Pasquale Cirulli, Zelo Surrigone (IT);
Mauro Scamporlino, Syracuse (IT);
Martin Ivar Franzen, Milan (IT);
Sofia Majan Capilla, Burgos (ES)
(73) Assignee: **PepsiCo, Inc.**, Purchase, NY (US)
(***) Term: **15 Years**
(21) Appl. No.: **29/685,121**
(22) Filed: **Mar. 26, 2019**

Related U.S. Application Data

- (63) Continuation of application No. 29/603,054, filed on May 5, 2017, now Pat. No. Des. 844,378, which is a continuation of application No. 29/539,850, filed on Sep. 17, 2015, now Pat. No. Des. 787,874.

(57) **CLAIM**

The ornamental design for a dispenser, as shown and described.

DESCRIPTION

FIG. 1 is a top front perspective view of a dispenser showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the figures show portions of the dispenser that form no part of the claimed design.
